(57) **CLAIM**

The ornamental design for a combined ceiling fan housing and blade iron, as shown and described.

DESCRIPTION

FIG. 1 is a perspective view of a combined ceiling fan housing and blade iron constructed in accordance with the present invention, the ceiling fan illustrates an environment for said fan housing and light;

FIG. 2 is an enlarged perspective view of a combined ceiling fan housing and blade iron in accordance with the present invention;

FIG. 3 is an enlarged perspective view of the combined ceiling fan housing and blade iron in accordance with the present invention;

FIG. 4 is an enlarged top view of the combined ceiling fan housing and blade iron in accordance with the present invention;

FIG. 5 is an enlarged bottom view of the combined ceiling fan housing and blade iron in accordance with the present invention; and,

FIG. 6 is an enlarged front view of the combined ceiling fan housing and blade iron in accordance with the present invention, the side views and the rear view being substantially the same.

The broken line showing of a ceiling fan canopy and blades is included for the purpose of illustrating environmental structure and forms no part of the claimed design.
